UNITED STATES PATENT OFFICE

131,699

DESIGN FOR AN AIR CIRCULATING PROPELLER

James M. Funk, Ottawa, Ill., assignor to Reynolds
Electric Company, Chicago, Ill., a corporation of
Illinois

Application September 3, 1940, Serial No. 44,767

Term of patent 7 years

To all whom it may concern:

Be it known that I, James M. Funk, a citizen of the United States, residing at Ottawa, in the county of La Salle and State of Illinois, have invented a new, original, and ornamental Design for an Air Circulating Propeller, of which the following is a specification, reference being had to the accompanying drawing, forming part thereof.

In the drawing:

Figure 1 is a face view of an air circulating propeller embodying my new design,

Fig. 2 is a side view of Fig. 1, and

Fig. 3 is a view similar to Figure 1, but taken on a line at about 45° to the axis of rotation, so as to show in full face view at least one of the three blades and more clearly indicate the shape of the blade where it joins to the hub.

I claim:

The ornamental design for an air circulating propeller, substantially as shown.

JAMES M. FUNK.
